Byers, Robbins & Farmer.

UNITED STATES PATENT OFFICE.

CHRISTIAN H. KENNEWEG, OF MILLVALE, PENNSYLVANIA.

SHOTGUN CARTRIDGE.

Application filed November 2, 1925. Serial No. 66,162.

To all whom it may concern:

Be it known that I, CHRISTIAN H. KENNEWEG, a citizen of the United States, residing at Millvale, county of Allegheny, and 5 State of Pennsylvania, have invented a new and useful Improvement in Shotgun Cartridges, of which the following is a full, clear, and exact description.

The present invention relates to shot gun 10 cartridges, and more particularly to a shot gun cartridge having its charge of shot so shaped as to scatter more than the usual spherical shot. The shot charge contains or consists principally of flattened shot, 15 which when discharged from the gun, scatter more than the usual shot.

By the use of such cartridges, choke bore shot guns may be used for close shooting in the same manner as an open bore shot gun, 20 or when used in an open bore shot gun an even greater scattering of the shot is obtained than is usual. In hunting in the woods or in thick growths or in tall grass, and so forth, the shot should have a large 25 pattern or spread which aids materially in the chance of striking the game in quick shooting and also prevents an excessive number of shot from striking and mutilating the game. Shot guns are bored to shoot 30 different patterns or spreads of shot, and may be divided into three general classes, i. e., full choke bore for long range shooting, modified or half choke bore for medium range shooting, and open or cylinder bore 35 for close shooting. By using cartridges having the scattering shot charges as herein described, a full choke or a half choke shot gun may be used for close shooting, and thus one shot gun may serve the hunter for shooting 40 at different ranges.

Referring to the drawings, which illustrate the preferred embodiment of the invention,—

Figure 1 is an elevation of a shot gun 45 cartridge taken partly in section;

Figure 2 is a similar view showing a modification; and

Figures 3 and 4 are enlarged detail views 50 showing respectively one of the flat shots in cross section and in elevation.

Referring to the illustrated embodiment of the invention, the cartridge consists of the usual shell 1 containing the usual powder charge 2, the usual gun wads 3 and a shot 55 charge 4. The shot charge 4 contains or

consists principally of flat shot. One of these flat shot is shown in enlarged detail in Figures 3 and 4. It consists of an ordinary spherical shot flattened or deformed into a disk-like shape, as shown in the drawings. This flattening may be conveniently carried out by passing the shot through rollers which are separated the distance desired for the thickness of the shot. When the shot are passed through rollers to flatten them, the flattened shot will not be perfectly circular, but will be approximately so. The shot are put into the cartridge in the usual way to form a charge of loose shot. The charge of shot may consist entirely of 60 flattened shot, as shown in Figure 1 of the drawings, or may consist partly of flattened shot and partly of the ordinary spherical shot as indicated by reference numerals 5 and 6, respectively, in Figure 2 of the drawings. By suitably proportioning the relative charges of flattened and of spherical shot, different patterns may be obtained. Also, by varying the amount of flattening of the shot, the scattering of the charge may be 65 varied. Thus, a hunter using a full choke barrel and carrying three lots of cartridges, i. e., some containing the usual spherical shot, others containing shot flattened somewhat and others containing shot flattened 70 still more, may use such gun to obtain a close pattern, a medium pattern and a wide pattern.

The flattened or irregular surfaces of the shot apparently so catch the air when discharged that the shot are scattered thereby. While I prefer to use the approximately circular disk-like shot, which are made by flattening the ordinary spherical shot, other forms of shot may be used, such, for example, as flattened shot having an angular instead of a circular outline. The present invention is therefore not limited to its illustrated embodiment, but may be otherwise embodied within the scope of the following 85 claims.

I claim:

1. A shot gun cartridge, having a scattering shot charge containing flattened shot, substantially as described. 105
2. A shot gun cartridge, having a scattering shot charge containing approximately circular disk-like shot, substantially as described.
3. A shot gun cartridge, having a scatter- 110

- ing shot charge containing shot having sufficient flattened surface so as to scatter more than the usual spherical shot, substantially as described.
5. A shot gun cartridge, having a scattering charge of loose shot consisting principally of flattened shot, substantially as described.
5. A shot gun cartridge, having a scattering charge of loose shot consisting principally of approximately circular disk-like shot, substantially as described.
6. A shot gun cartridge, having a scattering charge of loose shot consisting principally of shot having sufficient flattened surface so as to scatter more than the usual spherical shot, substantially as described.
- In testimony whereof I have hereunto set my hand.

CHRISTIAN H. KENNEWEG.
